FOLDING MACHINE

Filed Sept. 24, 1926

FIG. 2.

FIG. 3.

FIG. 4.

INVENTOR
ANDREW OLSON.

Kurt Hudson & Kent.
ATTORNEYS

UNITED STATES PATENT OFFICE.

ANDREW OLSON, OF CLEVELAND, OHIO, ASSIGNOR TO THE CLEVELAND FOLDING MACHINE COMPANY, OF CLEVELAND, OHIO, A CORPORATION OF OHIO.

FOLDING MACHINE.

Application filed September 24, 1926. Serial No. 137,451.

This invention relates to paper-folding machines of the type in which the paper is folded by a buckling operation as described in the Johnson Patent No. 893,629, dated July 21, 5 1908.

It is one of the objects of the invention to provide an improved form of mounting for the fold plate which will permit the same to be readily, conveniently and accurately 10 aligned with the folding rolls and avoid the usual fitting and trying, which has been heretofore necessary in connection with the manufacture of folding machines.

Other objects of the invention and the features of novelty will be apparent from the following description taken in connection with the accompanying drawings, of which:

Fig. 1 is a longitudinal section through a portion of the folding machine embodying 20 my invention, the section being on the line 1-1 of Fig. 2;

Fig. 2 is a section on the line 2-2 of Fig. 1;

Fig. 3 is an enlarged section on the line 3-3 of Fig. 1; and

Fig. 4 is a section on the line 4-4 of Fig. 1.

Referring to the drawings, 10 and 11 indicate the side members of the frame of the machine and 12, 13 and 14, the usual feeding and folding rolls. The fold plate is indicated 30 at 15 and is slidably mounted on the angle bars 16 and 17, which are secured on the members 10 and 11, respectively. As is well understood by those familiar with folding machines, it is necessary that the lower edge 18, 35 of the fold plate, be accurately aligned and positioned relative to the rolls 12, 13 and 14 and, according to prior constructions, this has required considerable trying and fitting of the fold plate, which has involved a considerable amount of time and expense in 40 building the machine. In order to overcome this disadvantage of prior construction, I have provided means for adjusting the bars 16 and 17, on which the fold plate slides, so as to properly locate the lower end 18, of the fold plate. Each of the bars 16 and 17 has, 45 as one of its securing means, a bolt 19 on which the bar is adapted to pivot. In this manner, the angle of the fold plate may be adjusted and the angle of either side of the fold plate may be adjusted independently of the other side by movement of one of the bars 16 and 17 on its bolt 19. In order to accomplish 50 this independent adjustment of the bars 16

and 17, I have provided the eccentric pins 55 20, which are mounted in the frame members 10 and 11, as shown in Fig. 4. The pins 20 extend through slots 21 in the bars 16 and 17 so that by rotating these pins, the lower ends of the bars may be raised or lowered, to properly align the lower end 18, of the fold plate, 60 with the rolls 12, 13 and 14. When this relation has been properly established, the bolts 19 are tightened and the pins 20 are secured in their adjusted position by any suitable device, such as a set screw or the device which will be presently described.

The fold plate is slidable on the bars 16 and 17 and, in order to confine it to its adjusted position, I provide stops 22 which engage the 70 transversely extending abutments 23, in the side edges of the fold plate. The fold plate is held down on the bars 16 and 17 by means of adjustable eccentric pins 24 and these pins may be similar to the pins 20 and, the method 75 of securing them is equally applicable to the pins 20.

The shanks 25, of the pins 24, are longitudinally split and there is a longitudinal opening through each pin 24, to receive the tapered 80 pin 26. When the pin 26 is driven into its opening, it expands the shank 25 so that the latter will be tightly secured in its opening in the frame. A set screw 27 is provided for the purpose of holding the tapered pin 26 in 85 the position to which it is driven. When it is desired to adjust the pin 24, the set screw 27 is removed and the pin 26 is driven to the left, in Fig. 3, thereby permitting the sections of the shank 25 to contract, so as to free the 90 pin from its opening in the frame. A screw driver may then be inserted in the slot 28 and the pin 24 turned to its desired position, after which the tapered pin 26 is again driven 95 tightly into its opening and the set screw 27 replaced.

Having thus described my invention, what I claim is:

1. In folding machines, the combination of a frame, a pair of supports on said frame, 100 a fold plate on said supports, feeding and folding rolls with which said fold plate cooperates, and means for adjusting said supports to align said fold plate with said rolls.
2. In folding machines, the combination 105 of a frame, a pair of supports on said frame, a fold plate on said supports, feeding and folding rolls with which said fold plate co-

operates, and means for independently adjusting said supports to align said fold plate with said rolls.

3. In folding machines, the combination of a frame, a pair of supports on said frame, a fold plate on said supports, feeding and folding rolls with which said fold plate cooperates, pivots on which said supports are mounted and permitting angular adjustment thereof, and members for adjusting said supports to align said fold plate with said rolls.

4. In folding machines, the combination of a frame, a pair of supports on said frame, a fold plate on said supports, feeding and folding rolls with which said fold plate cooperates, pivots on which said supports are mounted and permitting angular adjustment thereof, and rotatable eccentric members for

adjusting said supports to align said fold plate with said rolls.

5. In folding machines, the combination of a frame, a pair of supports on said frame, a fold plate on said supports, feeding and folding rolls with which said fold plate cooperates, bolts for securing said supports to said frame and on which the supports are angularly adjustable, rotatable eccentric members carried by said frame and engaging slots in said supports for the purpose of angularly adjusting said supports, and means whereby said eccentric members are secured in any position to which they are adjusted.

In testimony whereof, I hereunto affix my signature.

ANDREW OLSON.
